UNITED STATES PATENT OFFICE.

ALBERT WANNER, JR., OF HOBOKEN, NEW JERSEY.

DESIGN FOR A MIRROR-FRAME.

SPECIFICATION forming part of Design No. 25,517, dated May 19, 1896.

Application filed April 14, 1896. Serial No. 587,565. Term of patent 7 years.

To all whom it may concern:

Be it known that I, ALBERT WANNER, JR., residing in Hoboken, in the county of Hudson and State of New Jersey, have invented 5 and produced a new and original Design for a Mirror-Frame, of which the following is a full, clear, and exact description.

Reference is to be had to the accompanying drawing, which is a front view of a frame embodying my new design.

The design in its entirety comprises similar panels A A, a series of ornaments B B' B² along the bottom edge below the panels, a central ornament C, and end ornaments C' C² at 15 the top, and small side ornaments D. Each panel A includes a narrow flowered border *a* and corner ornaments, oppositely disposed, comprising each a plurality of conventionalized foliated scrolls *b*, ranging along the edges, 20 and additional conventionalized foliated scrolls *c c'* inside of and filling the angles formed by the scrolls *b*. The lower ornamental corners are at the inner angles of the panels and combined form an ornament centrally 25 of the frame, presenting a broad base extending both sides of the center and tapering toward the top. The bottom, top, and side ornaments also are composed in the main of conventional foliate scrolls. At the bottom 30 the ornaments B B' are disposed as feet, one at each side of the center, and curve toward

each other. The ornaments B' B' are disposed near the ends and range substantially in direction of the bottom edge, while the ornaments B² B² are also at the ends in the form 35 of feet and appear behind the ornaments B', the lower edges of the ornaments B² corresponding to ornaments B and projecting below ornaments B'. At the top the central ornament C is composed of a bust of a woman 40 with the arms raised above the head and a scrolled frame surrounding and supporting the bust. The end ornaments C' C² are arranged directly in front of the ornaments C² C², the latter ornaments rising the higher. 45 The ornaments D appear at the outer side edges of the frame at the four corners.

A leading feature consists in a frame presenting a panel with ornaments above and below the same at the corners. 50

Another leading feature is the panels having the narrow border with the opposite corners having the scrollwork, as shown.

I claim—

1. The design for a frame herein shown and described. 55
2. In a design for frames, the panels herein shown and described.

ALBERT WANNER, JR.
